(57) **CLAIM**

The ornamental design for a monitoring device, as shown and described.

DESCRIPTION

FIG. 1 is a front perspective view of a monitoring device; FIG. 2 is a rear perspective view of the monitoring device; FIG. 3 is a front view of the monitoring device; FIG. 4 is a rear view of the monitoring device; FIG. 5 is a left side view of the monitoring device; FIG. 6 is a right side view of the monitoring device; FIG. 7 is a top view of the monitoring device; and, FIG. 8 is a bottom view of the monitoring device. The broken lines in the drawings show portions of the monitoring device that form no part of the claimed design.
